SINGLE-LEVER WATER CONTROL

Raymond Stryzakoski and Joseph Cartabellatto,
New York, N. Y.

Application September 16, 1948, Serial No. 49,628

4 Claims. (Cl. 277—13)

1 This invention relates to new and useful improvements in plumbing appliances, and, more particularly, the aim is to provide a novel and valuable plumbing fixture, having a single swing-arm manually operable for simultaneously operating the shut-off valve in each of a cold water supply conduit and a hot water supply conduit, said two conduits leading to a common delivery faucet, and for controlling the discharge at said faucet of a mixture of the two waters as to obtain a faucet discharge of a temperature precisely as desired.

A further feature of the invention is that means are provided, also manually operable from said swing-arm (and regardless of its angular position for the use above described) for obtaining a desired discharge pressure at said delivery faucet, that is, to cut off, reduce or increase as selected the flow discharge at said delivery faucet.

The invention may be embodied as a self-complete plumbing fixture, or as an auxiliary fixture to be attached to two faucets, one a cold water faucet and the other a hot water faucet, as ordinarily installed one alongside each other, as over a tub or sink. As the invention is herein shown, by way of example, it is embodied as a self-complete fixture; but in a form comprising a plurality of separable main conduit units; to teach the use of the invention as an auxiliary fixture as above.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a partially broken away front elevational view of said embodiment, with the swing-arm aforesaid shown in one extreme position, to wit, the position for fully opening the shut-off valve in the cold water supply conduit and for fully closing the shut-off valve in the hot water supply conduit.

Fig. 2 is a top plan view of the assemblage.

Fig. 3 is a detail view, being a vertical section taken on the line 3—3 of Fig. 1, and, further, with one of the parts partially broken away.

Fig. 4 is a perspective showing the assemblage contained in a casing which may be provided therefor.

Referring to the drawings more in detail, the cold water faucet is marked 10, the cold water supply conduit 11, the hot water faucet 12, and

2 the hot water supply conduit 14; in each case the faucet being an integral continuation of its conduit.

Properly located adjacent the junction of the forward end of each such conduit with the upper end of its faucet, a cylindrical valve member is provided, such valve in the cold water line being marked 15 and such valve in the hot water line being marked 16. Each of said valves is secured to the lower portion of a shaft 17, the upper portion of which is journalled in a screw-cap 18 of the kind used for closing the top of an ordinary faucet in the usual way.

Since each of these valve members 15 and 16 is to be spirally raised for full opening, when the other valve member is spirally lowered for full closing, the valve member 15 has an external thread 15' matching an internal thread 15'' in the faucet 10, it being noted that said faucet has an upward tubular continuation above its junction with the cold water supply conduit 11, and that said thread 15'' along its upper portion is in said upward tubular continuation. Thus, with the valve member 15 fully raised as in Fig. 1, the upper end of the thread 15' on said valve member is at the upper end of the thread 15'' in the faucet. The pitch of these threads, as illustrated, is such that from top to bottom of the valve member 15 its thread 15' is of a length equal to one and one-half full turns. The thread 15'' is of twice this length, that is, it has a length of three full turns. Such thread 15'' is not continuous, but necessarily has a slight break at the opening 15* to be closed by the valve member 15.

The hot water valve member 16, of the same length and diameter as the valve member 15, has an external thread 16' matching an internal thread 16'' in the faucet 12, it being noted that said faucet also has an upward tubular continuation above its junction with the hot water supply conduit 14. With the valve member 16 fully lowered as in Fig. 1, the lower end of the thread 16' on said valve member is at the lower end of the thread 16'' in the faucet. The pitch of these threads, also, is such that the thread 16' is of a length equal to one and one-half full turns, and the thread 16'' is of twice this length, that is, its length is that of three full turns of the thread. Such thread 16'', like the thread 15'', is not continuous, but necessarily has a slight break at the opening 16* to be closed by the valve member 16.

Suitably fixed to the upper end of each shaft 17, above its cap 18, is a spur pinion 19.

An auxiliary unit 20 is provided interiorly with various intercommunicable water passages,

is secured rigidly to the lower open ends of the faucets 10 and 12. This securement is effected, at the upper ends of two laterally outwardly and then upwardly directed branch conduit portions 21 and 22, by means, in the case of each faucet, comprising a pair of clamp rings 23 and 24 and three tie-bolts 25. Said rings are matchingly apertured, with such apertures 120° apart, for taking said bolts; and there is interposed between each of the faucets and the associated conduit portion 21 and 22 a gasket 26.

The inner ends of the conduit portions 21 and 22 meet the lower end of a vertically upstanding conduit portion 27 and the upper end of a downwardly extending short conduit element 28 forming the upper subdivision of a delivery faucet 29 extending forwardly as shown in Fig. 2 and then downwardly as shown in Figs. 1, 2 and 4.

The shut-off and pressure control valve provided includes a valve seat 30, and a cylindrical valve member 31 fixed on the lower end of a vertically endwise movable rod 32. This rod extends up through the conduit portion 27 and through a screw-cap 33 for said conduit portion, for projection above said cap. At its top the rod 32 is formed to provide a ball 34. A bushing 37 is screw-threadedly secured in the cap 33; and said bushing serves to embrace the upper portion of the rod 32 to permit easy up and down endwise movement thereof, and also acts as a journalling means for a spur gear 35 meshing with the two spur pinions 19. Said gear 35 is held in mesh with the pinions 19 by an annular flange 36 carried exteriorly at the top of the bushing 37, as the pinions 19 rise and fall during lifting and lowering of the valves 15 and 16.

A single swing-arm actuator 38 is provided and includes a tube 39 fixed near its inner end in a bracket 40 secured as at 41 to the gear 35. On the outer end of said tube is fixed, as at 42, a handle section 43. Beyond the outer face of the latter, the tube 39 extends into another handle section 44. Rotatable in the tube 39 is a rod 45, with its outer end pinned as at 46 to the handle section 44. The inner end of the tube 39 is reduced in external diameter as at 47.

The ball 34 is a cam follower relative to a cam groove 48 partially formed in each of two members of like construction except for a hub portion carried by one of them, but of opposite hand; said members being shaped and coupled to provide a cam entity 49 for presenting said groove. The said cam entity is rotatively mounted as shown on the reduced inner end portion 47 of the tube 39; and is fixed to the inner end of the rod 45, as by means of a cotter pin 50 sent through the rod and also through the hub portion of that one of said members constituting the left half, as viewed in Fig. 1, of the cam entity 49.

Fig. 4 illustrates a casing 51, which may be used to enclose the entirety of the fixture, except for the handle-carrying end of the actuator 38, and except for the delivery faucet 29. At the front of the casing is a long horizontally extending slot 52, through which said actuator projects, and along which it is movable to cause rotation of the gear 35 in one direction or the other through somewhat less than 180°. A portion of the bottom wall of the casing 51 is shown in Fig. 1, this wall having an opening 53 for protrusion of the delivery faucet as shown in Figs. 1 and 4.

Operation

In any angular adjustment of the actuator 38 about the axis of the rod 32 as a center, the han-

dle section 44 may be turned relative to the handle section 43, thereby to turn the rod 45 to fractionally rotate the cam entity 49 and so raise or lower the valve member 31. As the parts are shown, the valve member 31 is fully lowered, shutting off any water discharge at the delivery faucet 29. When said valve member is fully raised, the full predetermined water pressure will be established at the faucet 29, which pressure may be modified as desired according to how much said valve is raised or lowered.

The actuator 38 has an angular swing about the axis of the rod 32 as a center, through substantially 180°, thereby to rotate the gear 35 through substantially a half revolution in one direction or the other; said actuator being shown in Figs. 1 and 2 at one limit of its said swing. The ratio of the pinions 19 to the gear 35 is one to three. Therefore, on each half revolution of the gear 35, both pinions will rotate through one and one-half revolutions, and so each of the valve members 15 and 16 will be rotated through one and one-half revolutions.

Because of the already described threaded connection 15'—15" between the valve member 15 and the faucet 10 and the already described threaded connection 16'—16" between the valve member 16 and the faucet 12, on swinging the actuator 38 to its position shown in Fig. 1 from its other limit of swing, that is, from its position indicated in dot and dash lines at 38a in Fig. 1, the valve member 15 will be spirally raised to fully open condition and the valve member 16 will be spirally lowered to fully closed condition; as shown in Fig. 1. Similarly, on swinging the actuator 38 from its position shown in Fig. 1 to its position indicated at 38a in that view, the valve member 16 will be spirally raised to fully open condition and the valve member 15 will be spirally lowered to fully closed condition. Similarly, also, on swinging the actuator 38 to cause the same to extend as indicated in dot and dash lines at 38b in Fig. 2, both of the valve members 15 and 16 will be in half open condition. Thus, according as the actuator 38 is swung into the selected one of a multitude of different positions, over a swing of the actuator through substantially 180°, precisely the desired mixture of hot and cold water may be obtained at the faucet 29.

While we have illustrated and described the preferred embodiment of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:

1. In a water control device having a faucet body including a delivery faucet and an upstanding conduit portion rising above the delivery faucet and connected to hot and cold water branch conduits including reciprocating shut-off valves having control pinions exposed on opposite sides of the conduit portion, a gear rotatively mounted on the top of the conduit portion and meshing with the pinions, a bracket mounted eccentrically on top of said gear, a tube having one end fixedly mounted in said bracket and its other end extended radially from said gear for turning the same, a valve seat within the faucet body below the conduit portion, a rod extended axially slidably through the conduit portion and having its top end projected from

the top of the conduit portion, a valve member on the bottom of said rod for seating on said valve seat, a second rod rotatably extended through said tube and having its inner end extended from the inner end of said tube, and means connecting the inner end of said second rod to the top end of said first rod to cause said first rod to be raised and lowered raising and lowering said valve member relative to said valve seat as said second rod is rotated in one direction or the other.

2. In a water control device having a faucet body including a delivery faucet and an upstanding conduit portion rising above the delivery faucet and connected to hot and cold water branch conduits including reciprocating shut-off valves having control pinions exposed on opposite sides of the conduit portion, a gear rotatively mounted on the top of the conduit portion and meshing with the pinions, a bracket mounted eccentrically on top of said gear, a tube having one end fixedly mounted in said bracket and its other end extended radially from said gear for turning the same, a valve seat within the faucet body below the conduit portion, a rod extended axially slidably through the conduit portion and having its top end projected from the top of the conduit portion, a valve member on the bottom of said rod for seating on said valve seat, a second rod rotatably extended through said tube and having its inner end extended from the inner end of said tube, and means connecting the inner end of said second rod to the top end of said first rod to cause said first rod to be raised and lowered raising and lowering said valve member relative to said valve seat as said second rod is rotated in one direction or the other, said connecting means including a cam means.

3. In a water control device having a faucet body including a delivery faucet and an upstanding conduit portion rising above the delivery faucet and connected to hot and cold water branch conduits including reciprocating shut-off valves having control pinions exposed on opposite sides of the conduit portion, a gear rotatively mounted on the top of the conduit portion and meshing with the pinions, a bracket mounted eccentrically on top of said gear, a tube having one end fixedly mounted in said bracket and its other end extended radially from said gear for turning the same, a valve seat within the faucet body below the conduit portion, a rod extended axially slidably through the conduit portion and having its top end projected from the top of the conduit portion, a valve member on the bottom of said rod for seating on said valve seat, a second rod rotatably extended through said tube and having its inner end extended from the inner end of said tube, and means connecting the inner end of said second rod

to the top end of said first rod to cause said first rod to be raised and lowered raising and lowering said valve member relative to said valve seat as said second rod is rotated in one direction or the other, said connecting means comprising a cam member mounted on the inner end of said second rod, said cam member having a downwardly facing cam groove, and a cam follower on the top end of said first rod and engaged in said cam groove.

4. In a water control device having a faucet body including a delivery faucet and an upstanding conduit portion rising above the delivery faucet and connected to hot and cold water branch conduits including reciprocating shut-off valves having control pinions exposed on opposite sides of the conduit portion, a gear rotatively mounted on the top of the conduit portion and meshing with the pinions, a bracket mounted eccentrically on top of said gear, a tube having one end fixedly mounted in said bracket and its other end extended radially from said gear for turning the same, a valve seat within the faucet body below the conduit portion, a rod extended axially slidably through the conduit portion and having its top end projected from the top of the conduit portion, a valve member on the bottom of said rod for seating on said valve seat, a second rod rotatably extended through said tube and having its inner end extended from the inner end of said tube, and means connecting the inner end of said second rod to the top end of said first rod to cause said first rod to be raised and lowered raising and lowering said valve member relative to said valve seat as said second rod is rotated in one direction or the other, said second rod having its outer end exposed beyond the outer end of said tube, and means mounted on the exposed outer end of said second rod by which a grip can be had thereon for manually rotating said second rod in one direction or the other.
